CLAIM

The ornamental design for a spray nozzle, as shown and described.

DESCRIPTION

FIG. 1 is a first top perspective view of a spray nozzle according to my new design;

FIG. 2 is a second top perspective view of the spray nozzle shown in FIG. 1;

FIG. 3 is a first bottom perspective view of the spray nozzle shown in FIG. 1;

FIG. 4 is a second bottom perspective view of the spray nozzle shown in FIG. 1;

FIG. 5 is a front side elevational view of the spray nozzle shown in FIG. 1;

FIG. 6 is a rear side elevational view of the spray nozzle shown in FIG. 1;

FIG. 7 is a top side view of the spray nozzle shown in FIG. 1;

FIG. 8 is a bottom side view of the spray nozzle shown in FIG. 1;

FIG. 9 is a right side elevational view of the spray nozzle shown in FIG. 1;

FIG. 10 is a left side elevational view of the spray nozzle shown in FIG. 1;

FIG. 11 is a left side elevational view of the spray nozzle shown in FIG. 1 in a first alternative position;

FIG. 12 is a left side elevational view of the spray nozzle shown in FIG. 1 in a second alternative position; and,

FIG. 13 is a top perspective view of the spray nozzle shown in FIG. 1 shown with an alternative spray nozzle head.

The broken lines in the figures are included for the purpose of illustrating unclaimed portions of the spray nozzle and form no part of the claimed design.

1 Claim, 13 Drawing Sheets
